(57) **CLAIM**

The ornamental design for a bathtub toy fastener, as shown and described.

DESCRIPTION

FIG. 1 is a top front isometric view of the bathtub toy fastener according to one embodiment of my new design; FIG. 2 is a bottom isometric view thereof; FIG. 3 is a front view thereof; FIG. 4 is a rear view thereof; FIG. 5 is a right side view thereof; FIG. 6 is a left side view thereof; FIG. 7 is a top view thereof; and, FIG. 8 is a bottom view thereof.

In the drawings, the even dash-dash broken lines depicts portions of the bathtub toy fastener that forms no part of the claimed design. The long-short broken lines depict the boundary of the claim that form no part of the claimed design.
